INVENTOR

William H. Hart

United States Patent Office.

WILLIAM H. HART, JR., OF PHILADELPHIA, PENNSYLVANIA.

Letters Patent No. 72,034, dated December 10, 1867.

IMPROVEMENT IN NECK-TIES.

The Schedule referred to in these Letters Patent and making part of the same.

TO ALL WHOM IT MAY CONCERN:

Be it known that I, WILLIAM H. HART, Jr., of the city and county of Philadelphia, and State of Pennsylvania, have invented a new and useful Improvement in Neck-Ties; and I do hereby declare the following to be a clear and exact description of the nature thereof, sufficient to enable others skilled in the art to which it appertains to fully understand and use the same, reference being had to the accompanying drawings, making part of this specification, in which—

Figures 1 and 3 are rear views of a "butterfly" illustrating my invention.

Figure 2 represents the application thereof.

Figure 4 is a modification.

Figure 5 represents its application.

Figure 6 is another modification.

Similar letters of reference indicate corresponding parts in the several figures.

My invention relates to improvements in that class of neck-ties or bows, of the "butterfly" order; and consists in applying to the rear of the bow or tie an elastic loop or cord, arranged horizontally or in line with the width thereof, and having its ends free, which ends are adapted to catch over or be fastened to studs or buttons on either a lie-down or stand-up collar, said studs or buttons being placed at points near the front button-holes, so that when the collar is buttoned in front, one stud will be on each side of the front button of the neck-band of the shirt.

The studs receive the ends of the loop, and thus support the bow or tie in place against the collar. The loop may have at each end a ring, to fit over the said studs or buttons, or a hook to catch in the openings made for the studs, or a hook and ring respectively; or a loop by itself may be passed over the studs, and form means for holding the ordinary neck-tie, thus obviating the necessity of running or passing it entirely around the neck.

By use of the above fastening or retainer, the back board or plate of a butterfly-bow or tie is entirely dispensed with; and this class of articles can be constructed much cheaper and quicker than formerly, and the tie or bow is readily applied and sets or fits neatly in place.

In the drawings, A represents a "butterfly" made of silk, linen, or other fabrics, paper, or any suitable material, and in the form of a bow or tie held together by the middle band *a*, as ordinarily. To the rear of this band *a*, I secure an elastic loop or cord, B, which will be united thereto at its middle, so as to leave its ends free. The loop or cord will lie horizontally in place or in the direction of the width of the bow or tie. The loop may be secured to the outside of the rear of the middle band *a*, as in fig. 3; that is, the clasp or fastening which holds the parts of the bow together will also take hold of the sides of the elastic loop, but leaves the ends free, thereby forming a loop on both sides of the fastening. Or the loop may be placed behind the middle band, as in fig. 1, that is, between the rear part of the band and the corresponding parts of the bow; and the spaces *b* between the sides of the loop are stitched or sewed together, so as to prevent the loop from falling out, but allow it to have a certain play to the right or left.

C represents an ordinary collar, of suitable material, and either of a lie-down or choker pattern, and having the usual button-holes, *a'*, in front, by which it is secured to the shirt by the retaining-stud or button *c* on the neck-band. The collar is cut or slit at points near the front button-hole, and in line therewith, with suitable slits, cuts, or openings, or button-holes, into which are introduced studs *D*, so that the front button will have a stud at both sides, placed in a row and in line with the length of the collar. Buttons might be sewed to the collar at the same points as the studs *D*; but as they would be inconveniences in washing the collar, it is desirable to use studs. In paper collars the studs are intended specially to be used. The proper openings could be made at the factory, along with the other parts of the collar, and thereby bring these collars into the market ready for the application of the studs, either by the seller or buyer.

In order to secure the bow or tie in place, one end of the loop is slipped over one of the studs, and then the other end of the loop is slipped over the other stud. The loop will bear firmly against the studs and draw them towards each other, and their resistance will cause the loop to be held tightly on the studs, and thereby retain the butterfly or bow snugly in place. The strain on the front button, as in ordinary fasteners, is entirely overcome in my device. It will be perceived that the elastic cord, drawing the ends of the collar together, will

release the front button from all pressure, and serve to give to the ends of the collar a certain direct lateral play, and thus allow them to yield or give somewhat while the wearer bends his head or turns it around. In order to release the bow or tie, one end of the loop is slipped off from the stud on which it is placed, when the other end is free, and allows the bow or tie to be removed at once. The advantage of having the loop slide between the band and the body at the rear of the bow is, that the projecting end of one side of the loop can be increased in size, and thus materially assist the operation of applying the bow. When said end is slipped over the stud the bow can be passed to that end, thus increasing the size of the other end, and rendering its attachment easily made. A very small loop may be used when applied in this manner. The loops may be provided at both ends with rings *d*, to catch over the studs or hooks *e*, to enter the openings *f* which receive the studs *D*, or with a ring at one end and a hook at the other; but these accomplish the same result as the loop and studs, and are therefore optional with the wearer. In lieu of an elastic loop, an elastic strap may be employed, having its ends turned into loops, or have secured to them the hooks or rings, for the same purpose as aforesaid. An independent loop, *B'*, fig. 6, may be placed over the studs *D*, and thereby form a support for the old style long neck-tie of half-length size. In this case there will be no strain on the front button, and the operation is the same as formerly described.

Should it be desired to run a neck-tie entirely around a choker or standing-up collar, and to use a butterfly therewith, the ends of said neck-tie may be slit or cut, so as to fit over the studs and thus hold the neck-tie in place. A loop may be secured to the back of the tie, on each side of the band *a*, and possess the same features as above.

It will be noticed that the supporting-plate or back, as in ordinary butterflies or supporters, is dispensed with; and I therefore produce a cheap device, which is alike simple and practical, and adapted for any style of collar, whether a stand-up or lie-down, and regardless of material.

I am aware that bows and ties have been retained in place by loops placed at the bottom of the tie or of its back plate, but these loops catch on the front button or stud of the neck-band of the shirt. These loops I do not, therefore, claim; neither do I claim a collar having studs or buttons for retaining separate loops, through which an ordinary long neck-tie is passed; but having thus described my invention,

What I claim as new, and desire to secure by Letters Patent, is—
A bow or tie, *A*, having an elastic loop or cord, *B*, arranged horizontally at its rear, with both of its ends free, for the purpose substantially as described.

To the above I have signed my name, this second day of November, 1867.

WILLIAM H. HART, Jr.
